UNITED STATES PATENT OFFICE.

AUGUST GERDES AND BURCHARD THOENS, OF NEW ORLEANS, LOUISIANA.

PROCESS OF DISTILLING WATER.

SPECIFICATION forming part of Letters Patent No. 425,316, dated April 8, 1890.

Application filed April 7, 1887. Serial No. 233,988. (No model.)

To all whom it may concern:

Be it known that we, AUGUST GERDES and BURCHARD THOENS, subjects of the Emperor of Germany, residing at New Orleans, in the 5 parish of Orleans and State of Louisiana, have invented new and useful Improvements in the Process of Distilling Water, of which the following is a specification.

In absorption ice-machines it is customary 10 to free the water from air prior to exposing the water to the refrigerating process in the usual freezing-cans for the purpose of producing clear and transparent ice-blocks.

In apparatus for depriving the distilled water of air serious objections exist, in that as 15 the coils through which the steam to be condensed passes are immersed in boiling water the temperature of which is too high to condense any amount of steam a large part es- 20 capes uncondensed, and hence imperfect condensation is the result; further, a large quantity of water is always kept boiling, and consequently much of it evaporates, and, finally, it is inconvenient to accumulate large quantities 25 of distilled water, which if left standing in tanks will reabsorb air and become unfit for making transparent ice free from a milky appearance.

The object our invention is to avoid the 30 above-mentioned objections and provide a convenient method of depriving distilled water of air for the manufacture of clear and transparent ice.

Figure 1 is a sectional elevation of a convenient apparatus for carrying our invention 35 into effect, and Fig. 2 a detail plan view of the final condensing tank and coil.

In order to enable those skilled in the art to make and use our invention, we will now de- 40 scribe the same in detail, referring to the drawings, where—

The letter *a* indicates the boiler or retort of an ordinary absorption ice-machine, and *b* is the steam-coil therein, having its inlet at *c*. 45 The pipe *d*, forming the coil in the boiler, rises and enters a heating-tank *f*, in which it is formed into a coil *e*, and then rises and is extended into another heating-tank *h*, where said pipe is formed into a coil *g*. The steam-coil 50 *e g*, it will be seen, is continuous through the two communicating tanks *f* and *h*, whereby we

utilize the sensible heat of the steam to boil the water in the first open tank *f*, and the latent heat to heat the water in the second water-tank *h* below the boiling-point, whereby 55 all the steam heat is utilized. The pipe then extends from the second heating-tank, rises upward as a branch *i*, with the delivery end arranged to discharge distilled water into the said second tank *h*. 60

The pipe *d* between the tank *f* and the boiler *a* is supplied with a cock or valve *s* and a valved pipe *r*, and the branch *i* is provided with a cock or valve *k*. The pipe *d*, forming the coils *a*, *e*, and *g*, is also provided with a 65 cock *l* directly outside the second tank *h*. The valved pipe *r* is designed to connect with a steam-boiler should it be desirable to condense steam direct from such boiler without passing it through the coil *b* in the retort *a*. 70 The tanks *f* and *h* are arranged side by side on a suitable support or flooring and are connected by a tube *m*, while the tank *f* is connected by a tube *n* with a cooler *o*, comprising, as here shown, a shell and vertical tubes. 75 The cooling-fluid enters by the pipe *p*, while the distilled water from the tank *f* enters the cooler by the pipe *n* and escapes at *q* in its cooled condition to be delivered to the freezing-cans of the ice-machine. The steam entering the coil *b* at *c* is partly condensed, and a mixture of steam and hot distilled water passes through the pipe *d* to the coil *e*, thence to the coil *g* and to pipe *i*, which delivers the same into the tank *h*, from which it passes 80 through tube *m* into the tank *f*. The steam which comes with water from the coil *b* boils the condensed water in the tank *f*, and by this boiling the air is expelled; but as the coil *e* is submerged in hot water in the heating-tank *f* 85 all of this steam is not condensed and some passes in coil *g*, submerged in the heating-tank *h*, where it is finally all condensed and flows as distilled water through the branch pipe *i* into the tank *h*. The passage of some 90 steam and hot water through the coil *g* maintains the water in the tank *h* near its boiling-point. By this arrangement a small amount of water only is kept boiling in the tank *f*, all the steam is condensed, and a large amount 95 of water is kept hot. If the water in the tank *h* is so hot as not to condense all of the steam,

- a second or third tank in every respect similar to tank *h* with coil *g* can be connected to it. By connecting these tanks and continuing the coils in same and emptying the distilled water from the coils into such tank or tanks *h* all steam will be condensed and a larger amount of water will be kept hot.
- Should the operation of the ice-machine stop for any length of time and a large amount of distilled water accumulate, which in becoming cool reabsorbs air, this water still can be used, because all water which is drawn off at the discharge-pipe *q* is compelled to flow through the tank *f*, where it is boiled and the air expelled as soon as the machine is set in operation again. The cost of the apparatus is thereby greatly reduced, as the accumulated distilled water can be kept in open tanks instead of in expensive air-tight vessels.
- We are aware that in ammonia-gas machines the condensed water has been boiled by steam in an open tank and cooled before using, so that the steam parts only with its sensible heat, as in Letters Patent No. 230,025.
- We are also aware that in ammonia-gas machines the steam has been condensed by cold water flowing over the steam-coil, so that the

cold water carries away and wastes the sensible heat of the steam, as in Letters Patent No. 214,161. Such, therefore, we disclaim as not of our invention.

Having thus described our invention, what we claim is—

The method herein described of depriving condensed water of air for the manufacture of transparent ice, which consists in carrying a mixture of steam and hot condensed water through connected hot-water tanks, boiling the water in the first tank by the passage therethrough of the said steam and water, heating the water in the second tank in a similar way, discharging into the latter the condensed water from the steam-pipes, returning the said water to the first tank, and finally carrying the boiled water to the cooler and thence to the ice-cans, substantially as described.

In testimony whereof we affix our signatures in presence of two witnesses.

AUGUST GERDES.
BURCHARD THOENS.
